Inventor:
Charles M. Richardson,

By Edmund H. Lany
Atty.

UNITED STATES PATENT OFFICE.

CHARLES MICHAEL RICHARDSON, OF INDIANAPOLIS, INDIANA.

BINDER.

Application filed September 2, 1924. Serial No. 735,379.

To all whom it may concern:

Be it known that I, CHARLES MICHAEL RICHARDSON, a citizen of the United States, residing at Indianapolis, in the county of Marion and State of Indiana, have invented 5 certain new and useful Improvements in Binders, of which the following is a specification, reference being had therein to the accompanying drawing.

10 This invention primarily relates to binders and, more especially, to memorandum order-binders, sales-books, and the like.

While the structure of my inventive concept is not restricted in its application, it 15 has a special utility as a binder for loose leaves or sheets, order-blanks, and the like. However, it may be advantageously used for binding larger sheets—on the order of post-binders.

20 One feature which is peculiar to my structure is that no stub, perforated or otherwise scored, is employed; and, also, that pressure is not resorted to to hold the leaves or sheets in place. In other words, I provide instruments—such as a binder device which 25 includes posts—for maintaining the leaves or sheets in position but, at the same time, permitting ready removal of one or more sheets without in any way disturbing the other sheets or the adjustment of the binding device, itself, forming a component of the structure. The sheets, nevertheless, are 30 at all times held evenly and securely.

It is contemplated among the objects of 35 the invention to provide a binder having outer cover members of permanent form and adapted to be used in conjunction with any number of sheets or fillers, and having, also, a binder device secured to one of the 40 cover members more or less permanently and provided with posts or lugs upon which the filler-leaves are carried and by which they are, for the most part at least, maintained in place. The binder device includes, in addition to the element secured 45 to the cover member, a detachable element of such construction as permits it to be interlocked with the permanent element and to become associated therewith by a sliding engagement and having a groove or an elongated depression with which the posts 50 on the permanent element register.

It is a further object of the invention to 55 provide a structure of this character where- in the component parts are of simple con-

struction, may be economically stamped from metal or the like and can be easily assembled.

Other objects and advantages will, in part, be apparent, and in part be brought 60 out more fully in the description which follows.

In the accompanying drawing is illustrated 65 one of several possible embodiments of the invention, and wherein:

Fig. 1 is a fragmentary view, in top plan, of a portion of a note or order book embodying my invention;

Fig. 2 is a similar view, in side elevation, and on an enlarged scale;

Fig. 3 is a fragmentary view, in section and on an enlarged scale, and taken on line 3—3, Fig. 4; and

Fig. 4 is a view in top plan of the structure with the leaves removed and the detachable element of the binder device out of position to show the relation of the co-acting parts.

In the drawing, the reference character 1 designates a cover member or back of a 80 book or the like, to which is secured a body-portion 2 of one component of a binding device, as by rivets 3.

Extending at an angle to this body-portion 2, there is an angulated portion 3' 85 upstanding from the surface of the cover portion, then bent back upon itself, and then carried downwardly in spaced relation to the upstanding portion to constitute a clip portion 4. Suitably mounted on the body 90 portion 2 are upstanding posts or lugs 5 which, in the present instance, are struck from the material forming the body portion of the binder device and upon which leaves 6 are adapted to be carried.

Co-acting with the component just described is another component, this having a top portion 7 provided with a ridge 8 struck into the metal to form a groove on its under surface for the reception of the outer or free ends of the posts 5. Extending from this portion 7 is an angulated portion 9, bent back upon itself to constitute a clip-portion 10, and carried in spaced relation to the portion 9. The arrangement is such that the two parts just described may be slid into interlocking engagement, the clip portions 10 on one component cooperating with the clip portion 4 on the other and maintaining the groove in the top 7 in contact with the tops 105 110

of the posts. Thus, it will be seen that the two components of the binder-device are interlocked with each other.

In use, it is merely necessary to slide the outer component out of interlocking engagement with the other component, whereupon the leaves may be removed or renewed. The provision of the described posts and interlocking elements permits the tearing out or removal of single leaves without interfering with the binding of the remaining leaves.

My inventive-concept is to be distinguished from structures, of a more or less similar character, which utilize pressure to hold the sheets or leaves in position, or which employ stubs and the like. In my structure, the clips do not bear with any appreciable pressure on the sheets, but these are held in place by the posts; and, being not clamped tight, any one or more of them may be removed from the binder-device without adjusting its component parts and, also, without disturbing the remaining sheets.

While the invention has been described in connection with the embodiment herein illustrated, it will be understood that I do not wish to be limited to the precise form of this disclosure, as many changes in the structure and arrangement of the parts are within the principles of the invention.

What I claim is:

1. A binder comprising coacting jaw-components, one of which includes a body-portion and an angle portion bent upon itself to constitute a clip, the other jaw-component likewise including a body-portion and an angle portion bent upon itself and constituting a clip, the two clips having an interlocking engagement and being slidable one upon

the other, and coacting means on these components for holding a plurality of leaves.

2. A binder comprising coacting jaw-components, one of which includes a body-portion and an angle portion bent upon itself to constitute a clip, the other jaw-component likewise including a body-portion and an angle portion bent upon itself and constituting a clip, the two clips having an interlocking engagement and being slidable one upon the other, and coacting means on these components for holding a plurality of leaves and including posts outstanding from the surface of a portion of one of the components and registering in a groove in a section of the other component.

3. A binder comprising a cover-member and coacting binder-components thereon, one of said binder-components including a body-portion and an angle portion bent upon itself to constitute a clip and the other binder-component likewise including a body-portion and an angle portion bent upon itself and constituting a clip, the two clips having an interlocking engagement and being slidable one upon the other, and coacting means on these components for holding a plurality of leaves.

4. A loose-leaf binder comprising a pair of coacting components each of which is substantially L-shaped in transverse section and has a portion of one of its legs bent back upon itself to provide an engaging clip, the two clips having an interlocking engagement and being slidable one upon the other, and coacting means on the components for detachably holding a plurality of leaves between the other legs of said components.

In testimony whereof I affix my signature.
CHARLES MICHAEL RICHARDSON.
